206,298

AIRCRAFT

Lawrence Bernard Rellis, 734 NW. 80th St., Apt. 16,
Miami, Fla.

Filed Mar. 7, 1966, Ser. No. 1,546

Term of patent 14 years

(Cl. D71—1)

Fig. 6

Fig. 7

FIG. 1 is a perspective view of the aircraft in climbing flight position, showing my new design.

FIG. 2 is a side elevational view thereof;

FIG. 3 is a top plan view thereof;

FIG. 4 is a view of the opposite side thereof;

FIG. 5 is a bottom plan view thereof;

FIG. 6 is a front elevational view in the landing position; and

FIG. 7 is a rear elevational view.

I claim:

The ornamental design for an aircraft, as shown and described.
